UNITED STATES PATENT OFFICE.

HENRY M. TOWER, OF SPENCER, MASSACHUSETTS, ASSIGNOR TO SMITH & HEMENWAY COMPANY, OF NEW YORK, N. Y.

DESIGN FOR A RAZOR-CASE.

SPECIFICATION forming part of Design No. 34,748, dated July 9, 1901.

Application filed April 17, 1901. Serial No. 56,827. Term of patent 7 years.

To all whom it may concern:

Be it known that I, HENRY M. TOWER, a citizen of the United States, residing at Spencer, in the county of Worcester, State of Massachusetts, have invented and produced a certain new and original Design for a Razor-Case, of which the following is a specification, reference being had therein to the accompanying drawing, which represents a perspective of the body of a razor-case.

As shown in the drawing, the design consists of a case or box body A, having a lower rectangular portion A' and an upper rectangular extension B of less diameter than the body, having at its base a straight line B', extending transversely about the several faces of the case, and upon one face thereof this line is deflected into a curved line B², forming a projection extending from the straight

line B' as a base and lying parallel with one side of the extension B. This projection formed by the curved line B² is flush with the lower portion A' of the case-body A, while the straight line B', forming a part of the perimeter of the case, provides a seat or shoulder portion between the lower portion A' and the extension B.

Having described my invention, what I claim as new, and desire to secure by Letters Patent, is—

The design for a razor-case as herein shown and described.

In testimony whereof I affix my signature in presence of two witnesses.

HENRY M. TOWER.

Witnesses:

IDA B. TOWER,
GEO. H. LARKUM.
